UNITED STATES PATENT OFFICE.

NATHANIEL WALTER STRATFORD, OF CHICAGO, ILLINOIS, ASSIGNOR TO THE BEARDSLEY & PIPER COMPANY, OF CHICAGO, ILLINOIS, A CORPORATION OF ILLINOIS.

SAND CUTTER.

Application filed December 4, 1926. Serial No. 152,552.

The invention relates to machines known as sand cutters of the character used in foundries in conditioning sand, preparatory to delivering it into moulds.

5 One object of the invention is to provide an improved construction in which the cylinder or drum is provided with elements for projecting or throwing sand from a hopper or receptacle, which are durable and are not likely to hook into or positively engage scrap castings oftentimes present in the sand, and this object is attained by providing elements on the cylinder which have their active portions formed of loops of wire for this purpose.

10 15 Another object of the invention is to provide a construction of this character which may be readily and conveniently applied to the drum, and this object is attained by utilizing a continuous flexible wire coil helically wound around the drum and secured thereon.

Another object is to provide means whereby the coil may be detachably and conveniently secured to the body of the drum or cylinder.

20 25 Another object of the invention is to provide yielding means coacting with the cylinder, such as coil springs having free ends terminating adjacent the throwing elements on the cylinder, for limiting the discharge of sand. Such springs are durable and may be secured

30 so they may be readily replaced.

Other objects of the invention will appear from the detail description.

The invention consists in the several novel features hereinafter set forth and more particularly defined by claims at the conclusion hereof.

In the drawings: Fig. 1 is a transverse section of a machine embodying the invention. Fig. 2 is a side-elevation. Fig. 3 is a longitudinal section. Fig. 4 is a detail of the body of the cylinder or drum. Fig. 5 is a plan, parts being omitted.

The invention is exemplified in a sand cutter of the wheel-cart type which may be moved around to discharge the sand wherever desired and comprises a pair of carrying-wheels 10 which support and are rotatable on a shaft 11; a frame or structure comprising side-brackets 12, through which the shaft 11 extends, and in which the shaft is fixed against rotation, and a pair of tubular handles 13 which are clamped in the brackets 12 respectively and by which the operator may move the machine to the desired point of opera-

tion; legs 14 secured to the handles; a receptacle or hopper 15 secured to and supported by brackets 12; and a cylinder for discharging the sand from the hopper for the purpose of disintegrating and distributing it. The cylinder comprises sand-throwing elements and a hollow cylindrical drum or cast body 16 on which the elements are secured. At either end, the body 16 is removably secured, by bolts 17, to heads 18 which close the ends of, and support, the cylinder. Said heads are carried by roller-bearings 19 around the shaft 11 and rotatably support the cylinder so that the latter may rotate around said shaft. The inner ring 19^a of each of said bearings is held by nuts 19^b which are threaded to the shaft 11. Caps 20, removably secured by bolts 21 to the heads 18, enclose the outer ends of bearings 19 and each has a gasket 22 fitting around shaft 11 to prevent sand from entering the bearings. This exemplifies a cylinder which is rotatable about a stationary shaft or axle and has its ends and its bearings completely enclosed to prevent the entry of sand into the cylinder.

Another object of the invention is to provide a cylinder directly driven by an electric motor which is disposed inside of, and enclosed by, the body of the cylinder, so that gearing will be dispensed with. The electric motor is of the induction type and comprises armature windings 25 and laminated fields 26 of usual construction. The armature is fixedly wound on and carried by the shaft 11, which is fixed against rotation relatively to the brackets 12, so that the armature windings will be nonrotatable. The fields 26, around

the armature windings 25, are fixedly secured in the cylinder-body 16. Preferably, the fields are secured together and pressed or driven into an inner cylindrical peripheral portion 27 or body 16 and against an annular shoulder 28 so they will be fixed to the cylinder and so that the flow of current through the armature will rotate the fields and drive the cylinder. A cable of conductors 29, for supplying current to the armature 25, leads therefrom through a radial opening 30 which leads to a longitudinal passage 31 in the shaft 11. Said passage extends to one end of said shaft. A socket 32 is secured by a screw 32^a to said end of the shaft. The wires 29 are connected to, and terminate at, contact-strips 32^b which are insulated from one another and secured in socket 32. The latter is adapted to detach-

ably receive a suitable connection-plug which is suitably connected to a source of current. This exemplifies a construction in which the electric motor for driving the cylinder is 5 mounted inside of, and enclosed within, the cylinder; which dispenses with gearing between the motor and the cylinder; in which the fields of the motor are secured directly in the cylinder body to drive the cylinder, and 10 in which the conductors enter the cylinder through the stationary motor-shaft.

In practice, it is desirable to provide sand-throwing elements which are durable, will not become broken, and may be easily replaced 15 when worn out. It frequently occurs that pieces of scrap or castings are present in the sand shovelled into the hopper 15, which, when rigid teeth or points are used for projecting the sand, are caught by the teeth and 20 projected with great force thereby, resulting in breaking or damaging the teeth or damage caused by the projected castings. To provide the cylinder with throwing elements which will meet these desiderata, the invention provides elements which consist of a series of 25 loops or ring-like elements 34, the outer arcuate portions of which engage the sand and are yieldable. For the convenience of producing and conjointly applying said elements, 30 they are formed of the loops or convolutions of a length of a coil of wire 35. The coil is spirally wound around the outer periphery of the cylinder-body 16 which is formed with a spiral concave seat 36 for the inside of the 35 coil. This coil is secured to the cylinder-body and in the groove 36 by a steel cable 37 which is threaded through the coil and has its ends anchored to bolts 39 which pass through lugs 38 integrally formed on the 40 outer periphery of the cylinder body 16 and adjacent its ends respectively. The outer ends of said bolts have nuts 40 whereby the cable may be drawn taut to secure the inner portions of the convolutions of the coil firmly in 45 the groove 36, leaving the opposite or outer portions of the convolutions free to flex circumferentially of the cylinder.

To house the end windings of the coil 35 and lugs 38, rings 42 are secured to the cylinder-body by the bolts 17 which secure the heads 18 and body together. Each ring 42 extends outwardly beyond the coil and longitudinally inward where it terminates in a flange 43 which is adapted to prevent the sand 50 from flowing endwise out of the hopper 15. Upon removal of the rings 42, the anchorages for the cable will be accessible so that the coil 55 may be removed and replaced when desired. This exemplifies throwing or projecting a 60 cylinder having its periphery provided with yieldable loops for engaging the sand. Thus formed, the elements are durable and avoid damage which results from the forcible projection of castings and the like which are in 65 the sand. It also exemplifies a construction

of this type of throwing elements, in which the entire series may be applied as a unit and conveniently secured to the cylinder-body.

The hopper 15 comprises inclined walls 15^a and sides 15^b which are preferably flared upwardly, so that sand may be shovelled into the hopper with facility, and a front wall 15^c. At that end of the hopper from which the sand is to be discharged, a transverse bar 44 is secured by bolts 48 to brackets 12, and a bar 45 extends across bar 44 and is secured thereto by bolts 47. These bars have vertically extending recesses 49 to receive and hold between them a series of coil springs 46 which have free lower ends terminating 75 adjacent the elements 34, to prevent an excess of sand from being discharged by the throwing elements and to coact with said elements in disintegrating the sand. The upper ends of springs 46 are removably clamped 80 between bars 44 and 45 by bolts 47.

The operation will be as follows: Sand will be shovelled or otherwise delivered into the hopper 15. When current is supplied to the electric motor in the cylinder, the latter will 90 be rapidly rotated so the outer portions of the elements 34 will throw sand from the bottom of the hopper onto, and distribute it over, the floor to cut the sand. Springs 46 will retard the sand in the hopper to prevent an excess from being discharged by the throwing elements.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a sand cutter, the combination of a frame, a cylinder rotatably mounted in the frame, sand holding means, resilient loops on the cylinder for throwing sand, and means for driving the cylinder.

2. In a sand cutter, the combination of sand-holding means, and driven means provided with a wire coil for throwing sand from the holding means.

3. In a sand cutter, the combination of a sand receptacle, and a driven cylinder-body provided with a wire coil for throwing sand from the receptacle.

4. In a sand cutter, the combination of sand-holding means, and driven means provided with a resilient wire coil for throwing sand from the holding means.

5. In a sand cutter, the combination of a sand receptacle, and a driven cylinder-body provided with a resilient wire coil for throwing sand from the receptacle.

6. A cutter element for a sand cutter, comprising a driven cylinder-body and a wire coil for throwing the sand, spirally wound around the body.

7. In a sand cutter, the combination of a sand receptacle, a driven cylinder-body, and a resilient wire coil spirally wound around the body, for throwing sand from the receptacle. 70
8. In a sand cutter, the combination of sand holding means, a driven cylinder-body, a wire coil for throwing sand, spirally wound around the body, and means for removably securing the coil on the periphery of the body. 75
9. In a sand cutter, the combination of sand holding means, a cylinder-body having a groove in its periphery, a wire coil for throwing sand, secured in said groove, and means for driving the cylinder. 80
10. In a sand cutter, the combination of a cylinder-body, having a spiral groove in its periphery, a wire coil for throwing sand, secured in said groove, sand holding means, and means for driving the cylinder. 85
11. In a sand cutter, the combination of sand holding means, a cylinder-body having a groove in its periphery, a wire coil for throwing sand, and a cable threaded through the coil for securing it on the body. 90
12. In a sand cutter, the combination of sand-holding means, a driven cylinder-body having a spiral groove in its periphery, a wire coil for throwing sand seated in said groove, and a cable threaded through the coil for securing it in the groove. 95
13. In a sand cutter, the combination of a cylinder body, throwing loops on the body, removable rings extending from the end portions of the body to enclose the loops at the ends of the body, and means for driving the cylinder. 100
14. In a sand cutter, the combination of a frame, a shaft in the frame, a cylinder-body rotatable around the shaft, a wire coil secured on the periphery of the cylinder, removable rings extended from the end portions of the periphery of the cylinder to enclose the outer sides of the ends of the coil, a receptacle for sand carried by the frame, and means for driving the cylinder. 105
15. In a sand cutter, the combination of a frame, a cylinder-body on the shaft, a wire coil spirally wound around the periphery of the cylinder, a cable threaded through the coil, attaching lugs for the cable on the body, removable rings enclosing the lugs and ends of the coil, a sand receptacle carried by the frame, and means for driving the cylinder. 110
16. In a sand cutter, the combination of a sand receptacle, a driven cylinder provided with elements on its periphery for throwing sand, and a series of coil-springs on the receptacle having their free ends extending to said elements and positioned to confine yieldingly the sand in the receptacle. 115
17. In a sand cutter, the combination of a sand receptacle, a driven cylinder provided with elements on its periphery for throwing sand, a series of coil springs on the receptacle having their free ends extending to said elements and positioned to confine yieldingly the sand in the receptacle. 120
18. In a sand cutter, the combination of a sand receptacle, a rotatable cylinder positioned to contact with the sand, and loops substantially covering the periphery of the cylinder, said loops being operative, during rotation of said cylinder, to cut the sand. 125
19. In a sand cutter, the combination of a sand receptacle, a rotatable cylinder positioned to contact with the sand, an annular series of loops extending around the periphery of the cylinder and operative, during rotation of said cylinder, to cut the sand. 80
20. In a sand cutter, the combination of a sand receptacle, a rotatable cylinder positioned to contact with the sand, and loops arranged in annular series around the periphery of the cylinder, said loops being operative, during rotation of the cylinder, to cut the sand. 85
21. In a sand cutter, the combination of a sand receptacle, a rotatable cylinder positioned to contact with the sand, and resilient loops substantially covering the periphery of the cylinder and operative, during rotation of said cylinder, to cut the sand. 90
22. In a sand cutter, the combination of a sand receptacle, a rotatable cylinder positioned to contact with the sand, and a continuous series of loops wrapped around the periphery of the cylinder, said loops being operative, during rotation of the cylinder, to cut the sand. 100
23. In a sand cutter, the combination of a sand receptacle, a rotatable cylinder to contact with the sand, and a continuous series of loops wrapped spirally around the periphery of the cylinder, said loops being operative, during rotation of the cylinder, to cut the sand. 105
24. In a sand cutter, the combination of means for delivering sand, a rotatable cylinder positioned to receive sand from said delivery means, and loops substantially covering the periphery of the cylinder, said loops being operative, during rotation of said cylinder, to throw the sand. 110
25. In a cutter mechanism of the character described, the combination of a sand hopper having a discharge opening at the bottom thereof and driven means positioned adjacent the discharge opening, and substantially covered with loops for throwing the sand as it is discharged from said opening. 120
26. A sand cutter element for a mechanism of the character described, said element comprising a body and resilient wire coil mounted on the body for throwing the sand. 125

Signed at Chicago, Illinois, this 19th day of November, 1926.

NATHANIEL WALTER STRATFORD.
